UNITED STATES PATENT OFFICE

JOSEPH A. READ, OF PHILADELPHIA, PENNSYLVANIA, ASSIGNOR TO
COMBS & BAWDEN, OF FREEHOLD, NEW JERSEY.

DESIGN FOR A FIRE-PLACE NICHE.

SPECIFICATION forming part of Design No. 15,493, dated October 28, 1884.

Application filed July 21, 1884. Term of patent 14 years.

To all whom it may concern:

Be it known that I, JOSEPH A. READ, a citizen of the United States, and a resident of Philadelphia, Pennsylvania, have invented or produced a new and original Design for a Fire Place Niche, of which the following is a specification.

My design for a fire-place niche is fully shown in the accompanying photographic illustrations, Figure 1 being a view of the complete niche, and Fig. 2 detached views of the fire-brick blocks comprising the lining of the lower part of the niche and the top rail of the same. The back of the niche has ornamentation in relief, comprising a horizontal band with semi-circular and A-shaped offsets, and above and below this band conventionalized representations of stems, leaves, and flowers. The top rail of the fire-brick lining has a vine-like ornamentation, and at the center, ends, and corners ornamentation of a geometrical pattern. The blocks composing the lower lining all have ornaments, comprising stems, leaves, flowers, and fruit, the central block having in addition

a series of oblong medallions, the corner blocks 25 having urns, and the side blocks ribbed medallions at the bottom.

I claim—

1. The design for the back of the niche, said design comprising the band with offsets and 30 the foliated ornamentation, as shown and described.

2. The design for the lower lining, said design consisting of the center, corner, and side blocks with ornamentation, as shown and de- 35 scribed.

3. The design for the niche, said design consisting of the upper back, the lower lining-blocks, and the topping rail, all ornamented as shown and described.

In testimony whereof I have signed my name to this specification in the presence of two subscribing witnesses.

JOSEPH A. READ.

Witnesses:

JOHN M. CLAYTON,
HARRY SMITH.
